The ornamental design for a shot glass, as shown and described.

DESCRIPTION

FIG. 1 is an isometric view of the shot glass embodying my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a left side elevational view thereof;

FIG. 7 is a rear elevational view thereof; and,

FIG. 8 is an elevational cross-sectional view thereof taken substantially in the plane on line 8—8 of FIG. 4.
